[57] CLAIM

The ornamental design for an article holder mounted on an automobile visor, as shown.

DESCRIPTION

FIG. 1 is a plan view of an article holder mountable on an automobile visor in the unfolded condition showing my new design;

FIG. 2 is a perspective view thereof in partially folded condition;

FIG. 3 is a perspective view thereof, in folded condition;

FIG. 4 is a front elevation view of FIG. 3;

FIG. 5 is a top plan view of FIG. 3;

FIG. 6 is a side elevation view of FIG. 3;

FIG. 7 is a bottom plan view of FIG. 3; and

FIG. 8 is a rear elevation view of FIG. 3.
